STEAM HEATED DRIER

Paul E. Ohlson and Edward A. Hodge, Wilmington, Del., assignors to The Pusey & Jones Corporation, Wilmington, Del., a corporation of Delaware

Application January 16, 1950, Serial No. 138,774

18 Claims. (Cl. 34—124)

1

The present invention relates to improvements in steam heated driers, such as are used in paper mills, food processing plants, industrial chemical manufacturing plants and the like.

The primary object of the invention is to increase the efficiency of such driers, without increasing the steam pressures employed and without increasing the size or materially increasing the weight of the driers.

A further object of the invention is to provide a drier construction in which the heat transfer rates are materially increased between the heating medium and the surface of the drier, at the same or reduced pressures, as compared to prior, conventional structures.

A further object is to provide a drier construction of the same or greater size in which the power required to drive the drier is very materially reduced, as compared to prior constructions.

Another object of the invention is to improve the condensate removal from the interior surface of a drying roll or the like, to the end that the formation of a layer of condensate on said surface is eliminated and the heat transfer between the steam and said surface is improved.

Another object is to increase greatly the speed of the flow of steam in contact with the inner surface of the drying roll, further to improve the heat transfer rate and the removal and elimination of air and condensate particles.

Another object of the invention is to prevent the creation of a layer or layers of condensate, rotating with the drier and thereby to reduce the power factor involved in rotating the driers, as compared with prior driers in which such layers of condensate were rotated therewith.

Another object of the invention is to provide a drier in which the steam for heating the periphery of the roll is delivered directly adjacent the inner surface of the rim, for high speed travel therealong and in which the condensate is immediately removed from said inner surface, as rapidly as formed, by a combination of forces, including gravity acting on the condensate, centrifugal force, and an inward scooping action resulting from the inertia of the condensate.

Another object is to provide means for moving the condensate radially inwardly relative to the inner face of the rim, substantially immediately as it is formed, so that the condensate is not permitted to form an insulating layer between the inner surface of the rim and the incoming steam.

Another object is to provide improved means for isolating the inwardly thrown condensate,

2

for collecting the same within the drier, out of contact with the heat absorbing surface, and for discharging the condensate from the collecting means to the outside.

Another object of the invention is to provide means within the dried adjacent the heat absorbing surface, in which a pulsating steam pressure condition is effected, so as to flash minute particles of condensate adhering to the heat absorbing surface, further to enhance the heat transfer.

Another object is to provide an improved system of connecting a plurality of driers in a line, such as a paper making line, in a novel series-parallel circuit, to improve the efficiency of the line.

Driers conventionally employed in industry are of two general types; first, the cast iron, hollow, steam heated driers, and second, the mild steel, jacketed driers. In the first, steam is conducted through hollow journals into the interior of the cylindrical drums or rolls, and the heat is transferred by the condensation of the steam upon the inner surface. At relatively high drier speeds, the condensate forms a layer or film of water entirely around the inner surface of the rim which acts as an insulator between the steam and the shell. In such case, the steam must heat the water which in turn heats the shell, an inefficient heat transfer system.

The condensation is conventionally removed by suction devices held stationary adjacent the bottom of the interior of the shell or mounted to rotate therewith.

In the mild steel, jacketed driers, steam jackets are associated with the inner surface of the shell and the steam is delivered directly thereto. However, the difficulties resulting from the presence of air, noncondensable gases, and substantial amounts of liquid condensate in the jacket spaces are not eliminated. The condensate often collects in the form of puddles, and the jacket spaces sometimes become water-bound. Moreover, the rate of steam flow through the jacket spaces is not sufficiently high to exert a scouring action, effective to remove air and non-condensable gases.

The present invention attains all of the advantages characteristic of both types of driers and eliminates the disadvantages thereof. Accordingly, the procedure previously followed in connection with cast iron driers is reversed. That is to say, the drier shell is heated directly with high velocity steam and the condensate and any particles of air are transferred inwardly

into an inwardly spaced collecting device, where the insulating effect of the water film and air cannot interfere with the transfer of the heat from the steam to the effective surface of the shell. The condensate so collected may be discharged from the drier before such a volume has accumulated as would increase the power required to rotate the drier with the water therein.

In spite of the fact that the present invention provides for high velocity steam flow directly in contact with the head absorbing surface of the drier shell and for immediate removal of condensate to a zone where it cannot act as an insulating layer, inhibiting heat transfer to said surface, the internal elements in the drier need not be steam tight, as is the case with the so-called jacketed drier.

The fundamental combination of the present invention comprises a sheet metal cylindrical shell, spaced inwardly a short distance from the inner surface of the cast iron rim, having a plurality of longitudinally extending vanes or fins projecting outwardly into contact with the rim and dividing the space therebetween into a plurality of longitudinally extending compartments; means for delivering the steam to these compartments behind the vanes or fins, for high velocity flow therein, and means for removing the condensate from the surface of the rim and causing the same to flow through the shell out of contact with the inner surface of the rim. The condensate so removed may be collected in various ways and then removed to the outside of the drier. An important feature of the invention is the forward inclination and axial angular disposition of the fins or vanes so that, as a result of the scooping action, the condensate flows axially, in one direction or the other, and then radially inwardly for collection and removal from the drier.

In accordance with the present invention, the cross-sectional area of the space between the inner surface of the cast iron rim and the outer surface of the internal shell, which may be termed the heat transfer space, is accurately controlled and proportioned with respect to the total area of the openings in the shell, leading from said space to the interior of the shell. By this accurate control and proportioning, the steam is caused to give up substantially all of its latent heat in the heat transfer space. The steam quality in this space may be reduced from 100% at a predetermined pressure to substantially 10%, at the same pressure, as it is discharged from the heat transfer space to the interior of the shell. This reduction in steam quality is the result of the transfer of the latent heat of the steam directly to the cast iron rim. It results, of course, in a very material reduction in volume, the pressure remaining the same, with a consequent high velocity flow in the heat transfer space, as will be apparent from the specific examples given below.

In the accompanying drawings, a number of specific embodiments of the invention are shown for purposes of illustration, but it must be understood that the drawings are illustrative only and are not restrictive of the invention, as many modifications and variations will occur to those skilled in the art from a consideration of the drawings and the following description.

In the drawings:

Figure 1 is a vertical, axial section of a preferred form of drier.

Figure 2 is a radial section taken on line 2—2 of Figure 1;

Figure 3 is a radial section, looking in the opposite direction, taken on line 3—3 of Figure 1;

Figure 4 is an enlarged fragmentary radial section, taken on line 4—4 of Figure 1;

Figure 5 is a fragmentary axial section on an enlarged scale, showing a preferred connection between the inner shell and the end of the drier;

Figure 6 is an enlarged fragmentary section with parts broken away, showing the condensate engaging fins or vanes, the section being taken substantially on line 6—6 of Figure 1;

Figures 7 and 8 are fragmentary sections and elevations taken on lines 7—7 and 8—8 of Figure 6;

Figure 9 is a fragmentary radial section, taken on the mid-section of the condensate collecting well or trough, showing a condensate discharge nozzle;

Figure 10 is a similar view, showing a discharge aperture, instead of the nozzle;

Figure 11 is a fragmentary radial section of a preferred form of joint between adjacent sections of the shell;

Figure 12 (sheet 1) is a fragmentary section and elevation of a modified form of steam outlet connection;

Figure 13 is a diagrammatic view of a steam and condensate distributing system for a plurality of driers;

Figures 14 and 15 are sectional and plan views of a preferred form of condensate removing scoop;

Figure 16 is a section and elevation taken on line 16—16 of Figure 14;

Figure 17 is a perspective view of a modified form of condensate removing scoop;

Figure 18 is a fragmentary section on line 18—18 of Figure 17;

Figures 19 and 20 are axial and radial sections of a modified shell construction; and

Figure 21 is a sectional detail on an enlarged scale.

The drier shown in Figures 1—4 comprises a heavy cast iron rim 20, supported at its ends by heads 21, 22, having hollow central bosses 23, 23', in which hollow journals, not shown, are fitted, so that the drier as a whole is carried by the journals for rotation about a horizontal axis. The heads and the cylindrical rim are hermetically sealed and provide a steam tight interior 25.

Spaced from the inner surface 26 of the rim is a cylindrical, sheet metal shell 27, which may be of stainless steel, Monel, or any other suitable material. Projecting from the outer surface of the shell are a plurality of groups or sets of vanes or fins 28, 29, 30, 31, pitched forwardly and outwardly in the direction of drum rotation, having their outer edges in contact with the inner surface of the rim, and disposed in angular relation to axial sections of the drum. Preferably, the angular disposition of each vane is such that its leading end is nearer to the head of the drier and its trailing end is nearer to the mid-section thereof.

The forwardly pitched vanes are preferably made in a plurality of angularly disposed sections, as shown at 28—31. Although only four sections, in generally endwise alignment, from one end of the drum to the other, are illustrated in the accompanying drawings, it should be understood that each vane may be considerably shorter and the number in each longitudinally extending group correspondingly increased.

The shell is provided with a plurality of spaced apertures 33, in alignment with and facing

toward the leading, inner surfaces of the vanes 28-31. The apertures 33 are of accurately predetermined size as pointed out below and provide openings for the inward flow of condensate, residual air and low quality steam as hereinafter explained.

The adjacent ends of the vanes 28 and 29, and 30 and 31, respectively, are interconnected by circumferentially extending relatively short angle member sections, one of which is shown at 34 interposed between the outer surface of the shell 27 and the inner surface 26 of the rim. Each angle section is spot welded to the shell 27 at a plurality of spaced points 36, Figure 7. The ends of the vanes 28, 29, etc. are held against the radial webs of the angle sections 34 by clamping plates 37, having their back surfaces recessed to receive the inwardly turned end flanges 38 and having their ends 39 welded to said webs.

Thus, the four sets of vanes 28-31 and their connecting angle strips 34 and 35 divide the space between the shell 27 and the rim 20 into a plurality of longitudinally extending compartments or steam spaces 40.

Disposed inwardly of the shell 27, behind the several apertures 33 are four pairs of inwardly projecting angle strip deflectors 41 and 42, arranged generally in endwise alignment, but in angular relation to axial sections of the drum and shell, with their leading ends adjacent the heads of the drum and their trailing ends adjacent the mid-section of the shell. As indicated in Figure 4, each angle member comprises a rearwardly extending flange 43 adapted to be secured by resistance spot welding or by rivets at a plurality of spaced points, to the inner surface of the shell 27; a radially inwardly extending web 44, and a forwardly turned flange 45 disposed on a surface substantially concentric to the shell 27.

At the inner ends of the angle strip deflectors 41 and 42, there are positioned a pair of circumferentially extending, parallel trough-forming angle members 46 and 47, having their outer circumferentially extending flanges 48 and 49 welded or riveted at a plurality of spaced points to the inner surface of the shell 27. At the points where the deflectors 41 and 42 abut the radial webs of the angle members 46 and 47, openings 46' and 47' are provided in said webs, for the flow of condensate from the deflectors into the trough space or well 50 therebetween, as explained below.

Referring to Figures 9 and 10, at the inner ends of the vanes 28 and 30, openings 33' may be provided, leading directly to the trough or well 50, or, if desired, these openings may be provided with short nipples 51 having caps 52 on their inner ends, provided with orifices 53 of accurately predetermined size.

For simplicity of manufacture, the inner shell is preferably made up of a plurality of sections, secured to each other by lap joints, the details of which are illustrated in Figure 11. One section 27a is provided with an axially extended, outwardly offset marginal portion 27b, upon which the marginal portion 27c of the next section 27d is lapped. The lapped marginal portions are apertured and are secured together by nuts and bolts 55.

Secured to the hollow central bosses 23, 23' of the drier heads are axially extending shaft means for accurately positioning the shell and serving to deliver steam to and remove condensate from the drier. A shaft 60 has its right

hand end secured in a socket member 61 carried by the boss 23' and its other end connected to a socket plate 62 mounted on a central distributing head 63. Concentric steam delivery and condensate return pipes 64 and 65 extend through the other hollow boss 23 at one end and are connected at their inner ends to the distributing head 63. The condensate return pipe 65 is connected to interior passages 66 in the head having two radial branches connected to curved pipes 67, leading to condensate scoops indicated generally at 68 and described below.

The outer, steam supply pipe 64 leads to an interior space within the head, separated from the space 66 and having two sets of four outlet nipples 70 and 71, to which two sets of radial steam delivery pipes 72 and 73 are connected. The latter are connected at their outer ends to steam headers 74 and 75, extending axially of the drum, behind the sets of vanes 28, 29 and 30, 31, respectively.

The headers 74 and 75 deliver steam to the spaces 40 between the shell 27 and the inner surface of the cast iron drier by connections shown in Figures 2 and 4. Short, radially extending pipe sections or nipples 76 are welded to the headers 74 and 75 at a plurality of spaced points, with attaching plates 77 secured thereto. The plates overlie openings 78 in the shell, through which the nipples 76 extend and these plates may be secured to the shell, if desired, by nut and bolt connections. The outer ends of the nipples 76 are closed as indicated at 79 and their side walls are slotted as at 80 so that steam is discharged laterally and does not impinge directly against the inner surface of the drier.

The shaft 60 and the outer steam pipe 64 are encircled by collars 81 having a plurality of sockets 82 for rods 83, constituting parts of turnbuckles 84, including rod extensions 85 having their outer ends seated in bosses 86 connected to the steam headers 74 and 75. Four of these turnbuckle assemblies are provided for each end section of the drier, so that the steam headers can be forced outwardly, firmly into engagement with the shell and the shell and vanes maintained in proper position.

If desired, the radial steam delivery pipes 72 and 73 may be constituted by flexible hose sections of suitable heat resisting material, connected to the central distributing head 63 and to the headers by conventional couplings.

Each vane 28-31 is preferably shaped in cross-section substantially as shown in Figure 4 and is made of relatively thin sheet metal having reasonably good spring characteristics, such as $\frac{1}{16}$ " thick stainless steel, so that the outer edge of the vane will bear against the inner surface of the drier with spring force and will conform to overall irregularities therein. A line of bend, as indicated at 90 in Figure 4 facilitates this conforming action.

The shell 27 may be secured to the inner faces of the end flanges of the drier shell by any suitable connection, such as that shown in Figure 5. The jacket may be bolted at spaced points to an end ring 91 which, in turn, is welded to a radial ring 92 having a groove 93 in its axial, outer face, for the reception of packing material 94, such as asbestos. The ring 92 may be secured to the end flange of the drier by screws 95 or the like.

Disposed in the central, inwardly facing channel or well 50 are a pair of suction nozzles or scoops 68, supported by radially extending rods

97 carried by the head 63. The rear ends of the scoops 68 are connected to the outer ends of the curved pipes 67, which are connected in turn at their inner ends by fittings 98 to the hollow interior 66 of the head 63. The details of certain preferred forms of scoops are shown in Figures 14-18 and will be described below.

In the operation of this form of the drier, steam delivered through the hollow journal and the hollow central shaft 64 fills the entire interior of the drier, since the shell does not have a steam tight fit, and, in any event, the steam is free to flow through the longitudinally extending compartments and apertures 33 to the interior. The steam flows with high velocity from the openings 80 in the nipples 76 into the compartments between the shell 27 and the inner surface of the rim. Condensate forms on the surface 26 of the rim, but is substantially immediately removed by the vanes 28-31, during the rotation of the drier. During the ascending portion of the rotational cycle, the condensate flows along the leading, inner faces of the vanes, toward the midsection of the drier, because of the angular disposition of the vanes. As a result of a scooping action and the force of gravity, the condensate flows inwardly through the apertures 33 to the inner surface of the shell 27, and along said surface until it strikes the deflector members 41 and 42. The flow along these members is in the same direction and the condensate is delivered through the openings 48', to the central well or trough 50.

During the descending portion of the rotational cycle, any condensate not removed from the deflector members 41 and 42 drops down, to be caught by the deflectors ahead thereof, on their ascending movement. The condensate collected on the inner surface of the shell thus flows longitudinally toward the mid-section, and is deposited by gravity and centrifugal force into the circumferential channel or well 58 where it is removed by the suction scoops 68.

The steam flowing through the spaces 31 between the outer shell 27 and the inner surface of the rim with high velocity exerts a scouring action on the inner surface of the rim, thereby removing air and non-condensable gases and preventing condensation from accumulating in a layer of substantial thickness. Also, the vanes 28-31 exert a pronounced scooping action on any condensate tending to form on the inner surface of the rim and tending to lag behind the rotational movement of the rim. As a result, a more efficient heat transfer is effected than is possible with prior constructions.

As noted above, the cross-sectional area of the space between the shell and the inner surface of the cast iron rim is accurately predetermined, and the relationship between this area and the sum of the areas of the openings 33 etc. leading from the space to the interior of the shell is accurately proportioned, preferably at a ratio of 10 to 1. The steam introduced at a predetermined pressure at 100% quality gives up its latent heat in the steam transfer space and its quality and volume are reduced by condensation, to a quality of 10% when the steam and condensate are delivered to the interior of the shell through the openings 33. This reduction in quality and volume results in high velocity steam flow in the transfer space. As an example, assuming the steam pressure to be 35 pounds gauge and the quality to be 100%, then the steam volume will be 8.5 cubic feet per pound (1174

5 B. t. u.) upon its injection into the heat transfer space, as will be found from any standard entropy diagram. Steam at 35 pounds gauge with a quality of 10% upon release from the heat transfer space will have a volume of 0.85 of a cubic foot per pound (330 B. t. u.), as will be noted from the entropy diagram. The reduction in volume is compensated for by the high velocity flow of steam in the transfer space, between the inlet nipples 76 and the condensate discharge openings 33.

10 The steam velocity is controlled by predetermining the sectional area of the annular space between the shell and the interior of the drier rim. For instance, if the input steam flow is 600 pounds per hour, at 35 pounds per square inch and the inside diameter of the drier is 46 inches and the outside diameter of the shell is 45 inches, by simple calculations, the cross-sectional 15 area of the transfer space is found to be 71.5 square inches or 0.496 square feet. The volume of the steam per pound at 35 pounds per square inch is 8.5 cubic feet, as may be noted on the entropy diagram. Thus, 600 pounds per hour 20 times 8.5 equals 5106 cubic feet per hour, or 85.1 cubic feet per minute.

25 Thus, the velocity within the transfer space will be 85.1 divided by 0.496 or 172 feet per minute. Steam velocity in this range is highly effective to displace and remove from the inside surface of the drier rim, condensate, air films and non-condensable gases, as compared with an ordinary drier in which the velocity has been found to be between 2 and 4 feet per minute.

30 35 The steam flow, regardless of pressure or volume is controlled essentially by the work done by the drier, i. e. the amount of heat transfer to the paper being dried, which may be measured in B. t. u.'s per hour. From consideration of a 40 standard entropy diagram, it will be noted that saturated steam at 35 pounds per square inch has a volume of 8.51 cubic feet at 100% quality and contains 1174 B. t. u. Steam at 35 pounds per square inch at 10% quality has a volume of only 0.851 and contains only 350 B. t. u. Hence, in the 45 above example, if the volume of the steam entering the heat transfer space is so controlled, before it is allowed to flow to the interior of the shell, that its quality drops from 100% to 10%, then the heat transfer is 824 B. t. u. at 35 pounds per square inch, the difference between 1174 and 350.

50 55 As noted above, the control of the steam quality and coincidentally of the volume is effected simply by making the area of the escapement openings from the heat transfer space just large enough to allow the steam to pass therethrough when it has reached 10% quality and not before.

56 60 In Figure 12 (sheet 1), there is shown a modification of the right hand end of the drier, so that a plurality of such driers may be connected in the manner shown diagrammatically in Figure 13, with a number of flash tanks in the circuit. In this arrangement, steam flows in parallel 65 through one pair of driers, and is delivered therefrom to flow in parallel to and through the next pair, while steam separated from the first pair joins the steam delivered therefrom and flows therewith through the next pair, and so on, as explained below.

66 70 The drier of Figure 12 may have substantially the same shell construction as described above, in connection with Figures 1-11.

75 76 Steam is delivered through the hollow journal to the distributing head and the radial pipes to

the headers and the space between the inner surface of the rim and the shell as previously described. Condensate is collected in the circumferential channel and removed through suction scoops, connected by the curved pipes to the hollow interior of a central shaft 100. The shaft is in communication with a pipe 106 (Figure 13), connected by another pipe 107 to a first flash tank 108, where steam and condensate are separated.

At its right hand end (Figure 12), the central shaft 102 carries an expansion joint 110 associated with a sleeve 111 having a plurality of apertures 112 therein, for the outward flow of steam, through the hollow journal 113 to pipe 116 (Figure 13). As shown in the latter figure, the first two driers 120 and 121 are supplied with steam, as explained immediately above, in parallel by a common supply pipe 115. The two condensate removal pipes 106 join the pipe 107 in parallel and deliver steam and condensate to the flash tank or steam trap 108. From this point, the condensate leaves by a pipe 116 and steam is delivered therefrom by a pipe 117. The two steam discharge pipes 114 from the first pair of driers are connected by a pipe 118 to the pipe 117, from which point, by a second pipe 119, steam is delivered to the next pair of rolls 122 and 123, in parallel in the same manner as in connection with driers 120 and 121. Condensate is removed from driers 122 and 123 by pipe 106a and pipe 107a to the second flash tank 108a. Steam discharged from driers 122 and 123, through pipes 114a joins the steam from flash tank 108a and is delivered to the next pair of driers 124 and 125 in parallel by a pipe 119b.

Assuming that the driers 124 and 125 are the last pair in the line, condensate and, possibly, some steam is discharged through pipes 106b and 107b to the final flash tank 108b.

Marked economy in steam consumption is effected by this system of steam distribution and condensate separation. It has been found particularly advantageous to have the steam space, between the shell and the inner surface of the cast iron rim, of progressively decreasing radial dimension, from the first pair of driers in the line, to the last. For instance, the steam space in the first pair of driers may be 2 inches; in the second pair, 1 1/4 inches, and in the third pair, 1 inch.

Actual tests have shown that, when steam at 35 p. s. i. pressure is delivered to pipe 115, the first pair of driers effect a heat transfer of 89,654 B. t. u.'s per hour; the pressure drop is such that in the next pair of driers, the pressure is 37.3 p. s. i., yet a heat transfer of 900,000 B. t. u.'s per hour is effected. In the final pair, the pressure is 22.5 p. s. i., with a heat transfer of 908,735 B. t. u./hr. The heat loss in such a system is extremely small, as compared with conventional systems, in most of which the steam flows from a source, in parallel, through all of the driers in the line. By making the steam space progressively smaller and by effecting a high velocity flow of steam, the heating medium may be conducted in series to successive pairs of driers and the steam normally lost in the steam traps or flash tanks returned to the line.

It is highly desirable in most instances, to prevent the escape of steam with the discharge of condensate, or to limit the amount of steam so discharged. Hence, the water rimming the bottom of the circumferential channel 50 should substantially seal the open end of the suction

nozzles or scoops disposed therein. Since the rate of accumulation of condensate in the channel varies in accordance with a number of factors, it is advantageous to make the mouth of each scoop or nozzle adjustable, to restrict the flow of liquid thereinto and to vary the height of the upper lip from the bottom of the channel.

A preferred embodiment of such an adjustable nozzle or scoop is shown in Figures 14-16. Referring to Figure 14, the nozzle is in the form of a flattened casting 130, terminating at its inner end in a hollow centrally tapped boss 131, into which one of the pipes, as pipe 67, is threaded. The casting is formed with a socket 132 in its upper or radially inner surface, in which the positioning rod 97 is seated. The lower or radially outer lip 133 may be secured in place by a pin 134 extending through the outer shell 27 and bearing against the inner surface of rim 20.

Interiorly secured to the lower surface of the upper lip 135 is a flexible stainless steel, spring lip 136, having an upwardly curved end 137. A screw 138, threaded in the forwardly projecting portion 135 of the nozzle 130, carries at its upper end a worm follower 139, in mesh with a worm 140 journalled in a bracket 141, positioned between spaced washers pinned to the screw 138. The worm is fast on a shaft 142, extending axially of the drier and, if desired, projected through one of the heads thereof, in steam tight relation, for ready manipulation from the outside. By rotating the shaft 142, the screw 138 may be projected into contact with the spring lip 136, to depress the same, more or less, toward the lower lip 133, thereby to vary the size of the effective opening between the upper and lower lips.

It should be noted that the side walls 143 and 144 of the nozzle project forwardly beyond the upper and lower lips and engage the side edges of the adjustable lip 136 with a fairly close, sliding fit.

It will be understood that the amount of condensate formed in each drier will depend upon the amount of heat transferred from the drier to the material being dried, such as the web of paper, in a paper making machine. This rate of heat transfer, in turn, is controlled by a number of variable factors, such as the steam pressure employed, the speed of rotation of the driers, the moisture content of the paper web, and the like. By manipulating the several worm carrying shafts 142, the movable lips associated with the suction scoops or nozzles may be adjusted so that a water seal in the condensate collecting channel or well is provided, thereby preventing the escape of undue amounts of steam to the steam traps or flash tanks, while permitting the discharge of condensate as rapidly as formed, and preventing the building up of excess amounts of condensate in the channels or wells.

The inclined vanes or fins 28-31 in the spaces between the outer shell and the inner surface of the cast iron drier are inclined forwardly and outwardly in the direction of rotation of the drier so that their leading edges are adjacent the surface of the drier and their trailing edges adjacent the outer surface of the shell. The vanes are also pitched from end to end, with their leading ends nearer to the heads of the drier and their trailing ends nearer to the mid-section. The apertures 33 in the shell are positioned in alignment with the inner, leading surfaces of the vanes adjacent the trailing edges thereof. The deflector members 41 and 42, projecting inwardly from the

shell, are positioned behind the apertures 33. The scooping action of the vanes, the influence of gravity, and the tendency of the condensate to lag behind the movement of the rim causes the condensate to flow in the V-shaped space between the outer surface of the shell and the leading face of each vane, lengthwise of the vane until one of the apertures 33 is encountered, whereupon the condensate is discharged into the interior of the shell. The condensate flowing along the inner surface of the shell encounters the inclined deflector strips 41 and 42 and is caused to flow along the leading faces thereof, toward and into the central well 50. The condensate is removed from the well 50 by the suction scoops previously described.

The periodic removal of condensate from the steam chambers or spaces between the shell and the rim, during each upward movement of the vanes and steam spaces, and the periodic covering and uncovering of the holes in the inner shell leading to the interior, results in a pulsating action and a periodic drop in pressure in the steam spaces, with consequent flashing of minute particles of condensate on the inner surface of the drier rim, which enhances the scouring action and eliminates the film of condensate normally present in other constructions, and which always has a high heat insulating effect. Hence, the transfer of heat from the steam to the drier surface is improved.

The form of condensate removal scoop shown in Figures 17 and 18 is preferred in some cases, for the sake of cheapness and simplicity of fabrication. It may be made of sheet metal parts, cut and bent to the desired shape and welded together. Disposed between the side walls 47a of the trough or well are a pair of parallel, radially disposed attaching plates 158, 151, having apertures 152 and 153 therein, by which they may be secured to the well. Welded to the rear ends of the plates 158 and 151 are a pair of inwardly converging side plates 154 and 155, connected at their rear ends to an apertured end plate 156. The outer edges of the plates 154, 155, and 156 lie against the bottom of the trough, in contact with the shell 27. The scoop structure is completed by an inner, top plate 158, welded to the side plates 154 and 155 and to the rear plate 156, and inclined outwardly and downwardly toward the bottom of the circumferential trough to a line 159, the outer or undersurface of which is spaced an accurately predetermined distance from the bottom of the trough. From this line forwardly, the plate 158 diverges from the trough bottom and inclines upwardly or inwardly to its forward edge 160, which is aligned with the edges of the side walls 47a and 48a. The side edges of the forwardly and inwardly inclined portion of the top plate 158 are preferably welded to the attaching plates 150 and 151.

The leading portion of the scoop acts as a mouth to receive condensate, while the restricted, slot-like opening below the transverse line 159 acts as a seal to prevent the escape of undue amounts of low quality steam. The condensate removal pipe 67a may have its end welded to the margins of the aperture in the plate 158.

In Figures 19, 20, and 21, a modified form of drier shell is shown. The steam delivery headers and pipes, the central shaft, the condensate removal scoops and pipes, and many other parts have been omitted, to simplify the showing, but it should be understood that the arrangements shown in the other figures of the drawings, or any

other appropriate construction may be employed with this form of shell.

The purpose of this modification is to effect a substantially uniform velocity steam flow within each of the heat transfer spaces or compartments, between each shell section and the drier rim, from the leading end to the trailing end thereof or, in other words, from the points where steam is delivered to the compartments to the points where the condensate flows inwardly to the interior of the shell. This substantially constant rate of steam flow is effected by decreasing or tapering the radial depth of each compartment, from the leading to the trailing end thereof.

It will be remembered that the pressure on both sides of the shell is equal. The removal of the latent heat from the steam in its passage through the spaces between the shell and the rim results in a reduction in the volume of the steam. If the compartments are of constant transverse cross-sectional area from end to end, the velocity of steam flow is decreased as the volume decreases. By the expedient of constantly decreasing the cross-sectional area of each compartment, in the direction of steam flow the reduction in volume is compensated for, and a substantially uniform velocity of steam flow may be effected.

Within the cast iron rim 160 is a substantially cylindrical shell 161, made up of a plurality of individual sections 162, each having its axial ends secured to circular flange members 163 and 164. The leading trailing ends of each section 162 are angularly disposed with respect to axial planes of the rim. The leading end of each section 162 is inwardly disposed in lapping relation to the trailing end of the next section, as clearly shown in Figure 21 and a filler strip 165 is preferably interposed therebetween, to space each leading edge a substantial distance, radially inwardly from the trailing edge of the adjacent section.

Projecting outwardly from the trailing edge of each shell section is a vane 166, which may be identical to the corresponding elements described above. Openings 167 are formed along the trailing edge of each shell section, adjacent the leading face of each vane 166.

Disposed inwardly of the shell are a plurality of angle strip deflectors 168, each secured to the leading edge of one of the shell sections 162, so that the deflectors are arranged angularly with respect to axial planes of the drier. The inner flanges 169 of each strip project forwardly, in the direction of rotation of the drier.

A condensate collecting well of the type described above may be provided within the shell, or a well may be formed adjacent one end of the drier, constituted by an inwardly projecting, circumferentially extending strip 170, adjacent the trailing ends of the deflectors 168. The strip is provided with a plurality of apertures 171, registering with the spaces adjacent the leading faces of the deflectors, at the trailing ends thereof, for the flow of condensate through the strip into the well.

Steam delivery nipples 172 extend through the shell sections at the leading ends thereof, as previously described and these nipples may be connected to steam supply pipes in the same manner.

By reference to Figures 19 and 20, it will be seen that the heat transfer spaces or compartments 175 are of tapering radial depth from their leading ends, adjacent the steam delivery nipples 172, to their trailing ends, where the holes 167 are located. This construction is particularly ad-

vantageous in the use of relatively high pressure steam, in which case the cross-sectional area of the heat transfer space and the radial depth thereof are reduced, as compared to constructions in which low pressure steam is employed. With the latter, steam velocities are relatively unimportant, since the velocity is less than with high pressure steam.

The operation of this form of the invention is substantially the same as previously described. Steam at relatively high pressure is delivered to the spaces 175, adjacent the leading ends thereof by the nipples 172. The steam flows through the spaces 175 toward the trailing ends and gives up its latent heat, resulting in a reduction of its quality and volume. Condensate is scooped inwardly by the vanes 166 and flows by gravity through the openings 167. The deflectors 168, which are inclined with respect to the axis of the drier impart longitudinal movement to the condensate, from their leading, right hand ends to their trailing left hand ends (Figure 19). The condensate flows through the wall 170 into the well at the left end of the drum, where it is removed by scoops, similar to any of the modifications shown and described above, but omitted from Figures 19 and 20.

It must be understood that the invention is not limited to the details of construction shown and described in this specification, but includes all modifications coming within the scope of the appended claims and their equivalents.

We claim:

1. A drier comprising a pair of rotatable heads and a cylindrical rim carried thereby and defining an enclosed interior, a cylindrical shell spaced from the inner surface of the rim, a plurality of longitudinally extending vanes projecting outwardly from the shell substantially into contact with the interior surface of the rim and dividing the space into a plurality of longitudinally extending compartments, means for delivering steam to each of said compartments, and means for conducting condensate radially inwardly through said shell from each compartment adjacent the leading face of the trailing vane thereof.

2. A drier comprising a rotatable, cylindrical rim, a cylindrical shell spaced from the inner surface of the rim, a plurality of longitudinally extending, forwardly pitched vanes projecting outwardly from the shell in contact with said surface and dividing the space therebetween into a plurality of longitudinally extending compartments, a plurality of apertures in the shell adjacent the leading faces of said vanes for the inward flow of condensate from the associated compartment under the influence of gravity and scooping action and means for delivering steam to each compartment.

3. A drier comprising a rotatable, cylindrical rim, a cylindrical shell spaced from the inner surface of the rim, a plurality of longitudinally extending, forwardly pitched vanes projecting outwardly from the shell in contact with said surface and dividing the space therebetween into a plurality of longitudinally extending compartments, a plurality of apertures in the shell adjacent the leading faces of said vanes for the inward flow of condensate from the associated compartment under the influence of gravity and scooping action and a plurality of conduits extending through the shell adjacent the trailing face of each vane for delivering steam to the associated compartment.

4. A drier comprising a rotatable, cylindrical

rim, a cylindrical shell spaced from the interior surface of the rim, a plurality of longitudinally extending vanes projecting outwardly from the shell into engagement with said surface of the rim and disposed in angular relation to axial sections of the rim and shell, whereby longitudinal flow is imparted to condensate engaging the same, said shell having a plurality of apertures therein adjacent the leading faces of the vanes, for the inward gravity flow of condensate engaged by the vanes, and means for delivering steam to the space between the rim and shell adjacent the trailing faces of said vanes.

5. A drier comprising a rotatable, cylindrical rim, a cylindrical shell spaced from the interior surface of the rim, a plurality of longitudinally extending vanes projecting outwardly from the shell into engagement with said surface of the rim and disposed in angular relation to axial sections of the rim and shell, whereby longitudinal flow is imparted to condensate engaging the same, said shell having a plurality of apertures therein adjacent the leading faces of the vanes, for the inward gravity flow of condensate engaged by the vanes, and means disposed inwardly of the shell for collecting condensate flowing through said apertures, means for conducting the same from the collecting means to the exterior of the drier and means for delivering steam to the space between the rim and shell behind the trailing faces of said vanes.

6. A drier comprising a rotatable, cylindrical rim, a cylindrical shell spaced from the interior surface of the rim, a plurality of longitudinally extending vanes projecting outwardly from the shell into engagement with said surface of the rim and disposed in angular relation to axial sections of the rim and shell, whereby longitudinal flow is imparted to condensate engaging the same, said shell having a plurality of apertures therein adjacent the leading faces of the vanes, for the inward gravity flow of condensate engaged by the vanes, and means for delivering steam to said space behind each of said vanes.

7. A drier in accordance with claim 5, in which said condensate collecting means comprises an inwardly facing, circumferential channel.

8. A drier comprising a rotatable cylindrical rim, a cylindrical shell spaced from the interior surface of the rim, a plurality of forwardly and outwardly pitched vanes projecting from the surface of the shell in contact with the inner surface of the rim, said vanes being arranged in a plurality of longitudinally extending, interconnected groups, dividing the space between the shell and the rim into a plurality of longitudinally extending steam compartments, each vane of each group being disposed in angular relation to axial sections of the rim and shell, said shell having apertures therein adjacent the leading faces of the vanes for the inward flow of condensate engaged by the vanes, means to engage the condensate flowing inwardly through the apertures and circumferentially on the inner surface of the rim, to impart longitudinal movement thereto, means defining a circumferentially extending well for receiving the longitudinally flowing condensate, and suction means in the well for removing the condensate therefrom.

9. A drier comprising a rotatable cylindrical rim, a cylindrical shell spaced from the interior surface of the rim, a plurality of forwardly and outwardly pitched vanes projecting from the surface of the shell in contact with the inner surface

of the rim, said vanes being arranged in a plurality of longitudinally extending, interconnected groups, dividing the space between the shell and the rim into a plurality of longitudinally extending steam compartments, each vane of each group being disposed in angular relation to axial sections of the rim and shell, said shell having apertures therein positioned at the trailing ends of the leading faces of the vanes for the inward flow of condensate engaged by the vanes, means to engage the condensate flowing inwardly through the apertures and circumferentially on the inner surface of the rim, to impart longitudinal movement thereto, means defining a circumferentially extending well for receiving the longitudinally flowing condensate, and suction means in the well for removing the condensate therefrom.

10. A drier comprising a rotatable cylindrical rim, a cylindrical shell spaced from the interior surface of the rim, a plurality of forwardly and outwardly pitched vanes projecting from the surface of the shell in contact with the inner surface of the rim, said vanes being arranged in a plurality of longitudinally extending, interconnected groups, dividing the space between the shell and the rim into a plurality of longitudinally extending steam compartments, each vane of each group being disposed in angular relation to axial sections of the rim and shell, said shell having apertures therein for the inward flow of condensate engaged by the vanes, a plurality of angularly disposed deflector baffle strips projecting inwardly from the shell behind the apertures to receive and engage the condensate flowing inwardly through the apertures and circumferentially on the inner surface of the rim, to impart longitudinal movement thereto, means defining a circumferentially extending well for receiving the longitudinally flowing condensate, and suction means in the well for removing the condensate therefrom.

11. A drier comprising a rotatable cylindrical rim, a cylindrical shell spaced from the interior surface of the rim, a plurality of forwardly and outwardly pitched vanes projecting from the surface of the shell in contact with the inner surface of the rim, said vanes being arranged in a plurality of longitudinally extending, interconnected groups, dividing the space between the shell and the rim into a plurality of longitudinally extending steam compartments, each vane of each group being disposed in angular relation to axial sections of the rim and shell, said shell having apertures therein adjacent the leading faces of the vanes for the inward flow of condensate engaged by the vanes, means to engage the condensate flowing inwardly through the apertures and circumferentially on the inner surface of the rim, to impart longitudinal movement thereto, inwardly projecting flange means at the ends of said baffle strips defining a circumferential well, said flange means being apertured to receive the longitudinally flowing condensate, and suction means in the well for removing the condensate therefrom.

12. A drier comprising a rotatable, cylindrical rim, a cylindrical shell spaced from the interior surface of the rim, a plurality of forwardly and outwardly pitched vanes projecting from the shell into contact with the inner surface of the rim, said vanes being arranged in longitudinally extending, interconnected groups extending in opposite directions substantially from the mid-section of the drier toward the ends and dividing the space between the shell and the rim into a plural-

5 16
ity of longitudinally extending compartments, each vane in each group being disposed in angular relation to axial sections of the rim with its leading end nearer to the adjacent drier head and its trailing end nearer to the mid-section, said shell having apertures therein adjacent the leading faces of the trailing ends of the vanes for the inward flow of condensate engaged by the vanes, and means within the shell for collecting and removing the condensate.

13. In combination with a cylindrical, rotatable drier having a closed interior, means spaced from the inner cylindrical surface thereof defining a circumferential space of relatively small radial dimension, means for delivering steam to said space at a plurality of spaced points, means for conducting condensate from said space and for causing the same to flow inwardly therefrom through the first mentioned means, deflector means for receiving the inwardly flowing condensate and for causing the same to flow longitudinally of the drier, means for collecting the longitudinally flowing condensate, and means for discharging the collected condensate from the drier.

14. A drier comprising a rotatable cylindrical rim, a substantially cylindrical shell spaced from the inner surface of the rim, a plurality of longitudinally extending, forwardly pitched vanes projecting outwardly from the shell in contact with said surface and dividing the space therebetween into a plurality of longitudinally extending compartments, a plurality of apertures in the shell adjacent the leading faces of said vanes for the inward flow of condensate, said shell having its outer surface disposed to give each of said compartments a tapering radial depth from its leading end, circumferentially towards its trailing ends.

15. A drier comprising a rotatable, cylindrical rim, a substantially cylindrical shell spaced from the interior surface of the rim, a plurality of longitudinally extending vanes projecting outwardly from the shell into engagement with said surface of the rim and disposed in angular relation to axial sections of the rim and dividing the space therebetween into a plurality of longitudinally and angularly extending compartments, and means for delivering steam to said compartments at the leading ends thereof, behind the trailing faces of said vanes, said shell having a plurality of apertures therein at the trailing ends of said compartments adjacent the leading faces of the vanes for the inward flow of condensate engaged by the vanes, said compartments being of tapering radial depth, from their leading ends in a circumferential direction toward their trailing ends.

16. A drier comprising a rotatable, cylindrical rim, a substantially cylindrical shell spaced from the interior surface of the rim, a plurality of longitudinally extending vanes projecting outwardly from the shell into engagement with said surface of the rim and disposed in angular relation to axial sections of the rim and dividing the space therebetween into a plurality of longitudinally and angularly extending compartments, means for delivering steam to said compartments at the leading ends thereof, behind the trailing faces of said vanes, said shell having a plurality of apertures therein at the trailing ends of said compartments adjacent the leading faces of the vanes for the inward flow of condensate engaged by the vanes, means to engage the condensate flowing inwardly through the apertures and to impart longitudinal movement thereto, means defining a circumferentially extending well for re-

ceiving the condensate from the last mentioned means and suction means in the well for removing the condensate therefrom, said compartments being of tapering radial depth, from their leading ends in a circumferential direction toward their trailing ends.

17. A drier comprising a rotatable, cylindrical rim, a substantially cylindrical shell spaced from the interior surface of the rim, said shell comprising a plurality of longitudinally and angularly disposed sections with the leading edge of each section disposed inwardly in lapping relation to the trailing edge of the adjacent section, to provide a space between each shell section and the rim of tapering radial depth from the leading edge to the trailing edge, a plurality of longitudinally and angularly extending vanes connected to the trailing edges of the shell sections and projecting outwardly therefrom into engagement with the inner surface of the rim, dividing said space into a plurality of compartments, means for delivering steam to each compartment adjacent the leading end thereof, and openings in the shell sections adjacent the trailing ends of the compartments for the inward flow of condensate engaged by the vanes.

18. A drier comprising a rotatable, cylindrical rim, a shell spaced from the inner surface of the rim and comprising a plurality of curved sections disposed in eccentric relation to the said surface and each having its leading and trailing edges on longitudinally extending angularly disposed lines, the leading edge of each section extending in inwardly spaced overlapping relation to the trailing edge of the adjacent section, and a filler strip between each of said overlapping edges, thereby providing a space between each section and the inner surface of the rim of taper-

ing radial depth from the leading to the trailing edge, a vane secured to the trailing edge of each shell section projecting outwardly into engagement with said rim surface and dividing said space into a plurality of compartments, means for delivering steam to each compartment adjacent the leading end thereof, and openings in the shell sections adjacent the trailing ends of the compartments for the inward flow of condensate engaged by the vanes.
